TENT

Michael J. McAuliffe, Vicksburg, Miss.

Application November 9, 1934, Serial No. 752,203

5 Claims. (Cl. 135—5)

My invention relates generally to improvements in tents and more particularly to a folding or collapsible tent or canopy particularly suited for use in carnival concessions, booths, as a sunshade for the lawn or beach or in any use where a completely enclosed tent is not necessary.

The main object is to provide a canopy or tent of this kind which may be permanently set up on the ground or other surface and which when in use will afford a protection against sun or rain and when not in use may be collapsed and folded up in a small space.

Another object is to provide a device of this kind including an umbrella-like fabric top or cover mounted atop a vertical supporting post and which may, when not in use, be folded up and completely enclosed by a weatherproof casing slideable on the post up over the said top.

A further object is to provide a device of the kind aforesaid comprising a vertical post, a plurality of radially extended ribs on the upper extremity of the post carrying a fabric cover or top and spring set to normally extend downwardly and outwardly to hold the cover stretched out taut, a casing slideable up over the post and spring set to normally move upward striking the ribs and folding them inward and upward together, the casing thus receiving and enclosing the folded ribs and cover and carrying a cap over its open upper end designed to close automatically and completely enclose the cover and protect it from the weather, there being of course means for holding the casing in a lowered position when the cover is expanded for use.

With these and other objects in view the invention resides in the novel construction and arrangement of parts as hereinafter fully set forth and claimed, reference being had to the accompanying drawings wherein:

Figure 1 is a side elevation of my invention as in expanded position ready for use, the collapsed and covered position of the parts being also shown in dotted lines.

Figure 2 is an enlarged fragmental view of the upper portion of the supporting post and associated parts, the cover, a part of the post and part of the casing being shown in section.

Figure 3 is an enlarged fragmental view of the lower portion of the post showing the fastening means for the casing, a part of the casing being again shown in cross section.

Figure 4 is a fragmental side elevation of a part of the supporting post showing the casing elevating spring and mounting.

In carrying out my invention I provide an up-

right supporting post 5 of a height suitable to support the hereinafter described tent cover at a distance above ground which will clear the heads of persons beneath, or of any suitable height, the post being suitably anchored at 6 in a base 7 which may be embedded in the ground or made portable as desired. Near the top of this post 5 a plurality of cover supporting ribs 8 are radially arranged and adapted to carry and support a cover or canopy 9 of canvas or similar waterproof fabric. These ribs 8 are of any suitable length according to the spread or size desired in the cover 9 and are pivoted by pins 10 between hinge lugs or ears 11 which are extended out from the post at radially spaced points. Torsional coil springs 12 are coiled around these pins 10 and their ends 13 are secured to the ribs 8 and the post 5 so that the springs normally tend to swing the ribs downward and outward to the position shown in Figure 2. In this position the cover 9 which is secured centrally to the post 5 at 14 and to the ribs at 15 is held expanded and taut as shown. Stay or brace ribs 16 equal in number to the main ribs 8 are pivoted at their inner ends by pins 17 between ears 18 radially extended from the post 5 below the aforesaid ears 11. At their outer ends these brace ribs 16 have eyes 19 turned up and slidably engaging slide rods or yokes 20 which are extended along in spaced relation beneath the outer end portions of the main ribs 8 and are held thereto by the upwardly turned ends 21 welded or otherwise secured to said main ribs. Now as the main ribs 8 reach the position at which they incline downward toward their outer ends and the cover 9 is taut these eyes 19 will move to the outer ends of the slide rods 20 and prevent any further downward movement of the ribs as will be understood. The hinge ears 18 are so located on the post that the brace ribs 16 will then rest in substantially a horizontal position as shown. Though thus locked against further downward movement the ribs 8 and 16 may be swung upward and together collapsing the cover 9 and forming a small compact bundle extended up above the post as shown in dotted lines in Figure 1. A casing 22 is provided to cover the folded ribs when in this position (Figure 1) and this casing is of tubular shape tapering from its upper to its lower end and having a cylindrical collar or sleeve 23 at its lower end which is freely and slidably mounted on the post 5. The casing 22 is thus supported on the post concentrically therewith with its open upper end 24 in position below the rib and cover assembly so that as the

casing is moved upwardly on the post this end 24 will strike the ribs and swing and fold them upwardly and together. The tapered shape of the casing is well adapted to receive the thus 5 folded ribs and cover assembly and the length of the casing is such as to completely receive and enclose these parts. A tapered or conical cap 25 is hinged by a spring hinge 26 to the side of the open end 24 of the casing 22 and as the casing is 10 raised over the ribs and cover, this cap 25 will be automatically closed by the spring 27 in the hinge 26 and will cover this open end of the casing. When the casing is pulled back down the cap 25 will be forced open and the ribs as they 15 are freed will swing down and apart to stretch the cover 9 by the springs 12. The cap 25 is then held in opened position (Figure 1) by a strap 28 secured to the casing 22 and engaged with a small knob or button 29 on the peak of the cap. 20 To aid in raising the casing 22 to enclose the ribs and cover, a flat torsional coil spring 30 is provided and is secured at one end 31 to an axle 32 which is journaled in and through a slot 33 in the post 5 and carries guide disks or plates 34. 25 The spring 30 normally coils around the axle 32 and the free end 35 is pulled down over a roller 36 in one corner of the slot 33 and is secured at 37 to the casing 22 near its lower end as shown. Now as the casing is pulled down this spring 30 30 is uncoiled and straightened out and its normal tendency to recoil tends to raise the casing as will be understood. The collar 23 at the lower end of the casing has a bayonet notch 38 which may be engaged with a pin 39 in the post 5 near its 35 lower end to hold the casing in lowered position against the pull of the spring 30. In lieu of this spring 30 a flat rubber band or strip might be used and arranged to be stretched as the casing is pulled down whereupon the band would tend 40 to again raise the casing.

From the foregoing it will be understood that by simply raising the casing 22 it will strike the ribs 16 outwardly of their hinge ears 18 and will swing these ribs and the main ribs 8 upward 45 folding and collapsing the cover 9 until the casing moves over and entirely encloses these parts. The cover is thus protected from the elements and the assembly may be left standing thus for any desired time. When it is again desired to 50 use the tent or canopy, the casing 22 is simply pulled downward and locked by the bayonet catch described as the ribs unfold and stretch the cover out taut. The whole structure may of course be made of any suitable size and for any desired 55 use.

While I have herein set forth a certain preferred embodiment of my invention, it is understood that I may vary from the same in minor structural details, so as best to construct a practical device for the purpose intended, not departing from the spirit of the invention and within the scope of the appended claims.

I claim:

1. In a device of the kind described, a post, a folding rib assembly on the post, and a casing slidably mounted on the post and adapted to cover the ribs when they are folded. 5

2. In a device of the kind described, a post, a rib and cover assembly foldably mounted on the post and a spring set to normally unfold and spread out said assembly, and means for automatically folding and enclosing the ribs and cover. 10

3. In a device of the kind described, a post, a plurality of radial main ribs hinged to the post and a spring set to normally swing the ribs outward and downward, a fabric cover secured on the main ribs, a plurality of radial brace ribs hinged to the post below the main ribs, slide rods mounted beneath and parallel to the main ribs, the said brace ribs having eyes at their outer ends slidably engaging the said slide rods, and means 15 for folding the said ribs upward together and enclosing and protecting the ribs and cover. 20

4. In a device of the kind described, a post, a plurality of radial main ribs hinged to the post and spring set to normally swing outward and downward, a fabric cover secured on the main ribs, a plurality of radial brace ribs hinged to the post below the main ribs, slide rods mounted beneath and parallel to the main ribs, and said brace ribs having eyes at their outer ends slidably engaging the said slide rods, and means for 25 folding the said ribs upward together and enclosing and protecting the ribs and cover, the same comprising a casing open at its upper end and tapered toward its lower end and slidably engaging the post, and a cap hinged to the upper end 30 of the casing and a spring set to normally close the said open end of the casing when the same is moved upward on the post to fold and enclose 35 the ribs.

5. In a device of the kind described, a post, a plurality of radial main ribs hinged to the post and a spring set to normally swing the ribs outward and downward, a fabric cover secured on the main ribs, a plurality of radial brace ribs hinged to the post below the main ribs, slide rods 40 mounted beneath and parallel to the main ribs, and said brace ribs having eyes at their outer ends slidably engaging the said slide rods, and means for folding the said ribs upward together and enclosing and protecting the ribs and cover, 45 the same comprising a casing open at its upper end and tapered toward its lower end and slidably engaging the post, and a cap hinged to the upper end of the casing and spring set to normally close the said open end of the casing when the same is moved upward on the post to fold and enclose 50 the ribs, spring operated means to normally raise the said casing, means for holding the casing in a lowered position and means for holding the cap in an opened position while the casing 55 is lowered. 60

MICHAEL J. McAULIFFE.
